INVENTOR

UNITED STATES PATENT OFFICE

105,162

DESIGN FOR A ROBE

Ralph D. Cooper, New York, N. Y.

Application May 7, 1937, Serial No. 69,210

Term of patent 3½ years

To all whom it may concern:

Be it known that I, Ralph D. Cooper, a citizen of the United States of America, residing in Manhattan, county of New York, and State of New York, have invented a new, original, and ornamental Design for a Robe, of which the following is a specification, reference being had to the accompanying drawing, forming part thereof, wherein,

The characteristic feature of my design resides in the combination on the robe as shown of the embroidery on the blouse section.

I claim:

The ornamental design for a robe, substantially as shown, and described.

RALPH D. COOPER
